UNITED STATES PATENT OFFICE.

GEORGE SWAN, OF GRAND VIEW, OHIO.

WOOD-BORING MACHINE.

SPECIFICATION forming part of Letters Patent No. 375,223, dated December 20, 1887.

Application filed June 28, 1887. Serial No. 242,741. (No model.)

To all whom it may concern:

Be it known that I, GEORGE SWAN, a citizen of the United States, residing at Grand View, in the county of Washington and State of Ohio, 5 have invented certain new and useful Improvements in Wood-Boring Machines; and I do hereby declare the following to be a full, clear, and exact description of the invention, such as will enable others skilled in the art to which 10 it appertains to make and use the same.

My invention relates to wood-boring machines; and it has for its object to provide a durable and inexpensive machine of simple construction, with an interchangeable gearing 15 to increase or decrease the speed of the spindle and an auxiliary shaft to increase the power and facilitate the operation of the machine, as well as a pressure-bar to feed the drill; and it consists of the parts and combinations of parts hereinafter described and claimed.

In the accompanying drawings, forming a part of this specification, Figure 1 is a front elevation of my machine; Fig. 2, a vertical 25 section on the line *x* *x*, Fig. 1; Fig. 3, a detail view of the bit-socket; Fig. 4, a plan view of the machine; Fig. 5, a detail view, and Fig. 6 a detail view showing a part of the supporting-arm *T* and the cross-bar *B*.

30 Similar letters refer to similar parts throughout the several views.

A represents two uprights, which are joined or secured together at their upper and lower ends by cross-bars *B*; and *C*, a base or bed frame, to one end of which the uprights are secured by hinges *a*, so that the uprights may be adjusted to any desired angle or folded on the base for packing. On each side of the bed-frame one end of quadrantal guides *D*, having 35 slots *c*, are pivoted, and also to the sides of the uprights by thumb-screws *b*, passing through the slots *c*, whereby the uprights are securely held in their adjusted position.

E is a sliding frame consisting of the uprights *e*, joined together by the cross-bar *f* near their lower ends, and having bearings for the shaft *F* near their upper ends. The uprights *e* are grooved along their lengths at their outer sides to fit tracks *g*, formed on the 45 inner sides of uprights *A*, and along which the carriage slides. Projecting outwardly 50

from the uprights *e* of the carriage are the brackets *h*, in which the auxiliary shaft *H* has its bearings. On each end of this shaft crank-handles *m* are secured, and between one of these 55 handles and the bracket *h*, on one side of the machine, a small spur-cog, *G*, is secured on the shaft *H*, which meshes with a cog-wheel, *G'*, secured to one end of the shaft *F*. The other end of the shaft *F* carries a fly-wheel, *K*, to 60 balance the shaft. Between the uprights *e* a large bevel-wheel, *L*, is mounted rigidly on shaft *F*, and meshes with a small bevel or crown wheel, *M*, rigidly secured to the upper end of the spirally-grooved spindle *N*, said bevel-wheel *M* and spindle being supported by the cross-bar *f*, through which the spindle passes.

On spindle *N*, above the cross-bar *P*, a collar, *O*, is secured by a set-screw, so that it may be adjusted thereon at different heights to 70 throw or trip the trigger, hereinafter described, at the desired depth of bore, and thus reverse the travel of the spindle. A cross-bar, *P*, having an enlarged central portion, *p*, through an opening in which the spindle passes and is 75 guided, is secured at each end to the uprights *A*. At one side of the enlarged portion *p* of the cross-bar *P* a notch is formed in the upper edge, and in the cross-bar at that side a slot is formed in which a pin, *r*, having a thumb-piece, *s*, thereon, is inserted, as indicated by the dotted lines in Fig. 1, a spiral spring, *t*, being fitted beneath the thumb-piece in the groove and bearing against an offset on the pin to throw it forward, when the forward 85 end of the trigger *T*, which is pivoted between the walls of the slot and projects into and above the notch in the enlarged portion, is depressed by the collar *O*, thus raising its rear end and releasing the pin, so that it may enter an 90 opening in the enlarged portion *p* of the cross-bar *P*, said opening being in line with the slot in the cross-bar, so that the pin will engage the spiral groove in the spindle and thus reverse the direction of travel of said spindle 95 and withdraw the auger or bit from the wood in which it is working.

R represents a pressure plate having its under side or surface concaved, so as to fit the shaft *F*. This plate is supported and operated 100 by a screw-rod, *S*, the lower end of which works in the plate, and which passes through

a screw-threaded opening in a supporting-arm, T', one end of which is fitted in a dovetailed slot, m^2 , formed in the upper cross-bar, B, so as to be easily removed when desired, as 5 clearly shown in Fig. 6.

The object of the plate R is to stop the upward movement of the spindle when the auger has been completely withdrawn from the wood and prevent the carriage working up off the 10 tracks. When a drill or reamer is used, however, the plate acts also as a pressure-feed therefor, the operator in this case working the machine with one hand and using the other to feed the drill to its work by turning 15 the screw and forcing the plate down on the shaft F of the carriage, while his weight, as it is customary for the operator to sit on the base, prevents the machine from rising up.

As clearly shown in Fig. 5, the cog-wheels 20 G and G' are provided with square eyes for the square ends of the shafts F and H, the eyes of both wheels being the same size, so that they may be changed from one shaft to the other to change the speed of the spindle. 25 Thus when the small wheel G is on shaft H and the large wheel on shaft F the machine is adapted for heavy work with a large auger, and when they are changed from one shaft to the other the speed of the spindle will be 30 greatly increased, suitable for small augers, drills, &c.

The lower end of spindle N is screw-threaded, as shown, for the purpose of securing the bit-stock A' (see Fig. 3,) thereto. This stock is 35 screw-threaded internally at one end and formed with the ordinary tapering socket, h', at the other end to receive the end of the bit. At one side a recess, a', is formed in the stock 40 opposite the tapering socket h', and has an opening, b', entering the same. In this recess a double-armed lever or catch, c', is pivoted, one arm of which projects outwardly slightly beyond the outer surface of the stock, while the other arm enters the opening b'. A spring, 45 d', is secured in a downwardly-extending continuation, h², of the recess a', and has its free end working or pressing against the lever, the tendency being to keep that arm of the lever which enters the opening b' always thrown inward, while pressure on the other arm will 50 force the same out against the spring. The object of this device is to securely hold the bit, which is notched to receive the end of the arm of the lever in place ready for operation,

while a slight pressure on the other arm, forcing the same inward, will release the same and permit the bit to drop out. 55

Having thus described my invention, what I claim as new, and desire to secure by Letters Patent, is—

1. A boring-machine consisting of the base C, the hinged uprights A, having the tracks g on their inner sides, sliding frame or carriage E, the grooved uprights e and cross-bar f, the brackets h, auxiliary shaft H, having its bearings in said brackets, the interchangeable gearing G G', the cranks m, the shaft F, having its bearings in uprights e and carrying the balance-wheel K and bevel-wheel L, the latter being located between said uprights, the 65 spirally-grooved spindle N, supported in the cross-bar f, the bevel-wheel rigidly attached to the upper end of said spindle, the collar O, adjustably secured on said spindle, the slotted cross-bar P, having the enlarged portion p, the 70 trigger and pin located in said slotted bar, a suitable bit-stock, and a pressure-plate removably secured in the frame of the machine above the sliding frame and adapted to press said frame downwardly, as set forth. 8c

2. The combination, with a boring-machine having a sliding frame, of the arm T', removably secured in the main frame of the machine, the screw-rod S, working in said arm, and the pressure-plate R, having a concaved under 85 surface adapted to fit the main shaft of the machine, substantially as described.

3. The combination, in a boring-machine, of a spindle having a screw-threaded lower end, a bit-stock having one end internally 90 screw-threaded and its other provided with a tapering socket, a continuation-recess formed in said stock opposite to and communicating with said socket and having a downwardly-extending continuation, a lever having two 95 arms projecting at right angles therefrom pivotally secured in said recess, and a spring having one end rigidly secured in the continuation of the recess and the other or free end working against said lever, substantially as 100 described.

In testimony whereof I affix my signature in presence of two witnesses.

GEORGE SWAN.
